Allen A. TIRRILL,

UNITED STATES PATENT OFFICE.

ALLEN A. TIRRILL, OF SCHENECTADY, NEW YORK.

ELECTRIC SWITCH.

1,161,361.

Specification of Letters Patent. Patented Nov. 23, 1915.

Application filed October 28, 1909. Serial No. 525,227.

To all whom it may concern:

Be it known that I, ALLEN A. TIRRILL, a citizen of the United States, residing at Schenectady, in the county of Schenectady 5 and State of New York, have invented certain new and useful Improvements in Electric Switches, of which the following is a specification, reference being had therein to the accompanying drawing.

10 This invention relates to improvements in snap switches, and while the several features of the present invention are capable of use in devices of various types, the general construction and arrangement is primarily designed for use as a ceiling or wall switch.

More specifically the invention comprises a switch of simple and efficient mechanism of compact form mounted for insertion into a recess, whereby to lie substantially flush 20 with, the surface of a ceiling or wall.

The preferred embodiment of the invention embraces the utilization of a pull cord or chain adapted in conjunction with the working parts of the switch, by successive 25 pulls on the cord or chain, to make and break contact with the electric wiring.

Novel characteristics of the invention reside in the mounting of the operating mechanism of the switch upon a frame and covered by a flush plate whereby the former 30 may be inserted and removed intact with the latter; the formation and arrangement of the switch mechanism whereby the same may be readily inserted and fixed within an ordinary junction box or casing; and means enabling the affixing of the switch mechanism to any of a number of different sized junction boxes or casings, thus enabling service of my improved switch as a substitute 35 for others already in use in connection with what may be styled the standard types of boxes or casings.

The details in the construction and arrangement of the parts of a structure made 45 in keeping with the present invention will be apparent from the detailed description hereinafter contained when read in connection with the accompanying drawings forming part hereof and wherein a convenient embodiment of the invention is illustrated.

In the drawings: Figure 1 is a perspective view of the switch as it appears in the ceiling or wall, Fig. 2 is a side elevation of the box removed from the ceiling or wall 55 and with the switch secured therein, Fig. 3 is a vertical longitudinal section through Fig. 2, Fig. 4 is a horizontal section taken on the line 4—4 of Fig. 3 looking in the direction of the arrows, Fig. 5 is a rear elevation of 60 the flush plate and the supporting frame to which it is normally secured, Fig. 6 is a face view of the insulating casing for the switch mechanism which in turn is inserted in the junction box or flush pocket, Fig. 7 is a rear 65 elevation of Fig. 6, Fig. 8 is a vertical sectional view on the line 8—8 of Fig. 6 looking in the direction of the arrows, Fig. 9 is a horizontal section on the line 9—9 of Fig. 6 looking in the direction of the arrows, Fig. 10 is a detail elevation of one of the 70 combined binding posts and spring contact supports, Fig. 11 is a similar view of one of the spring contacts, and Figs. 12, 13 and 14 are detail views illustrating the ball and chain 75 attachment.

Referring more specifically to the drawings, wherein like reference characters designate similar parts in the several views, A represents the surface of an ordinary ceiling 80 or wall in which latter a recess of adequate size and shape is formed for the reception of a junction box B into which the wiring, as desired for lighting circuits, etc., leads, said box being conveniently of an ordinary 85 or standard type, removably secured in place through the medium of apertured ears b projecting outwardly therefrom for the accommodation of fastening screws or nails, as is usual, and hence unnecessary to show 90 herein. At the forward edges of the top and bottom walls of the box B, threaded apertured portions b' are formed within which securing screws C are designed to engage in a manner to fasten the face plate D and 95 mechanism carried thereby, to the box B as will now more fully appear. The flush plate D is provided with an aperture fitted with a bell-shaped tube d rounded at its edges for the passage of a pull cord or chain 100 E operating in a manner to be later pointed out, and the plate is of a size to overlie the

surface of the ceiling or wall A bordering the pocket or recess therein to cover the opening thereof, but the plate being formed quite thin and beveled at its edges offers no substantial protrusion from said surface.

On the rear of the plate D I secure a supporting frame having in turn a flat base F and arms G, G'. The ends of the frame F are offset slightly in an outward direction 10 as at f to fit complementary recesses f' in the rear face of the plate D, these offset portions having apertures c for the screws C heretofore referred to and which engage the threaded apertures b' of the box B. I have 15 shown two apertures c at each end of the frame to illustrate the adaptability of the device to different sizes of boxes B, the screws C being shown in the drawing as passing through the inner-most apertures c, 20 whereas in cases where larger boxes B are in use, the screws would pass through the outermost apertures as is obvious. To fasten the flush plate D on the frame portion f of the bracket, screws d' are passed through 25 the plate D into engagement with threaded apertures f' formed in the base F.

The arm G of the frame is formed integrally with and turned inwardly from the frame F, the same being apertured as at g' 30 for the passage of a shaft h which carries the switch blades H. The bracket G' is preferably formed separately from the frame F and has a flange g' underlying the base accommodated by a recess g' in the 35 back of the plate D, this flange being secured to the frame through the medium of screws g'. The inner end of the bracket G' is apertured as at g' in alinement with the aperture g' of the arm G also for the blade 40 carrying shaft h.

Save for the spring contacts with which the switch blades are adapted to engage, and the special ball and chain attachment to be hereafter referred to, it will be unnecessary to herein specifically describe the details 45 of the switch or the operating mechanism which manipulates said blades to make and break contact, as desired, it being sufficient to here note that said mechanism by a progressively rotating actuation of the blades causes the latter to engage and be disengaged from the spring contacts. This operating mechanism is clearly described and shown and constitutes the subject matter of 50 a copending application executed by me of even date herewith, filed October 28, 1909, Serial No. 525,226.

When the switch is used in a ceiling, the pull cord or chain will preferably be of an 60 elongated type, but when used in a side wall, I conveniently employ a short chain and ball attachment illustrated in Figs. 12 and 13, the same comprising a chain 2 provided at one end with a pull ball 3 made of hard rub-

ber molded material or porcelain, the ball 65 being secured to the chain by a small snap washer 4 passing over the chain between the links, and which washer may readily slide into the recess 5 in the ball and engage the shoulder 6 therein. In this way the ball is 70 freely mounted on the chain and may be readily removed by simply slipping the ball upwardly on the chain and removing the snap washer. The opposite end of the chain is provided with a connecting device 4', 75 having an offset T head 7, adapted to detachably engage a slotted portion 8 in the operating sheave, and with an offset snap catch 9 to engage between the adjoining links of the chain. The chain may be of any 80 desired formation, but as shown, has rounded or ball links which will readily slide through the bell-shaped tube d in the flush plate D.

Housing the switch mechanism is a porcelain cup or casing I secured to the frame F 85 by screws i passing through ears i' in the cup and engaging threaded apertures i' in the frame. The back of the cup is grooved, as at i' i'' for the accommodation of screws i'' and to enable the use of a wire connection 90 in the groove i'', it being obvious to those skilled in the art that this switch can be made either single pole, double pole, three-way, two circuit, three circuit, four way, etc. The screws i'' secure in place and are 95 in electrical connection with four combined wire terminal connecting and spring contact supports J, one arranged at each corner of the porcelain cup I, the fastening being had by the screws i'' engaging threaded apertures j in an offset base flange j'. The outer end of each device J is also offset as at j' 100 and provided with a lug j'' adjoining a threaded opening j', the relation of the lug and opening being such that the head of a 105 binding screw J' may oppose the lug and co-operate therewith in securing the wire terminals thereto. One of the spring contacts which is adapted to receive and electrically engage with the rotatable switch blades H 110 is shown in detail in Fig. 11, the same comprising adjacent spring arms K having oppositely flaring ends k and held in yieldable relation through the medium of a connecting portion k' formed flat and occupying a 115 position at right angles to the arms K, this connecting portion being formed flat as shown, whereby to lie against the contact support J and be firmly secured thereto by rivets L passing through alined apertures 120 l l' in the connecting portion k' of the contact and in the intermediate portion of the contact support J. As shown in Fig. 3 of the drawings, the rotation of the switch blades H is in planes parallel to the side 125 walls of the porcelain cup I, and the spring contacts K being arranged in horizontal positions and extending from the rear wall of

the cup forwardly therefrom, the contacts are at all times held in the path of rotation of the switch blades H whereby to alternately make and break contact therewith, 5 as is apparent.

From the foregoing description it will be appreciated that the improved switch disclosed herein is insertable into boxes B already placed in walls, or may be installed in 10 new boxes placed in either ceiling or wall, as desired, and that as an article the device may be readily handled and sold intact owing to the connection of the porcelain box I to the frame F which carries the switch 15 mechanism and the connection of the frame F with the flush plate D. To install or remove the switch from the box B, it is simply necessary to fasten or unfasten the screws d' and C. It will be obvious that the screws 20 C may also be inserted through the flush plate D instead of simply through the frame F, if desired.

In the hereto appended claims, wherein I employ the words "pull cord", it is obvious 25 that this term is to comprehend a cord, chain, or other pull mechanism.

I will not claim herein the means for connecting the ball to the pull chain, nor the device for connecting the pull chain to the 30 switch, inasmuch as these more properly constitute subjects matter for divisional applications.

I claim:—

1. An electrical switch comprising a cup, 35 contact devices secured to the interior of the cup, a progressively rotatable switch member mounted within the cup provided with means adapted to coöperate with the contact devices, and mechanism for operating the 40 switch member with a snap action including a pull cord.

2. An electrical switch comprising a cup, contact devices secured to the interior of the cup, a rotatable switch member mounted 45 within the cup provided with means adapted to coöperate with the contact devices, and mechanism for operating the switch member including a pull cord.

3. An electrical switch comprising a cup, 50 contact devices secured to the interior of the cup, switch blades that are progressively rotatable parallel to the side walls of the cup into and out of engagement with the contact devices, and mechanism for operating said blades including a pull cord.

4. In a switch of the character described, 55 a cup, contact devices secured to the rear wall of the cup and projecting forwardly therefrom, switch blades rotatable in planes parallel to the side walls of the cup toward and from the rear wall thereof into and out of engagement with said contacts, mechanism for operating said blades, and means for supporting said mechanism removably

engaging said cup, said operating mechanism including a pull cord projecting outwardly from the front of the cup. 65

5. In a switch of the character described, a cup, contact devices secured to the rear wall of the cup and projecting forwardly 70 therefrom, switch blades rotatable in planes parallel to the side walls of the cup toward and from the rear wall thereof into and out of engagement with said contacts, mechanism for operating said blades, and means 75 for supporting said mechanism removably engaging said cup, said operating mechanism including a pull cord projecting outwardly from the front of the cup, in combination with a face plate through which 80 the pull cord passes.

6. In combination with a combined wire terminal securing device and contact support comprising a fastening portion, and a portion fashioned for the attachment of a 85 terminal wire, a contact formed of a single piece of metal, and comprising an attaching portion adapted to be secured to said support, portions extending at right angles to said attaching portion and extending there- 90 above to provide a pair of yieldable arms, said yieldable arms being provided at the free ends thereof with contact portions spaced throughout the length thereof and extending parallel to said support, the opposite ends of said contact portions being 95 flared outwardly.

7. In a switch of the character described, a cup, contact devices secured to the interior of said cup, a plate closing the end of said 100 cup, a rotatable switch member carried by said plate and adapted to coöperate with the contact device on the interior of the cup, an operating mechanism for said rotatable switch member including a pull cord pro- 105 jecting outwardly through the plate closing the end of the cup.

8. In combination with a junction box, a face plate adapted to lie upon the open end of said junction box and provided with recesses in the end portions thereof, a bracket plate removably secured to the rear face of 110 said face plate, and provided with off-set portions lying in the depressed portions of said face plate, a cup secured to said bracket 115 plate, contact devices positioned within said cup, a switch member carried wholly by said bracket plate and adapted to coöperate with the contact device in said cup, and means adjustable longitudinally of the off-set portion 120 of said bracket plate for securing said plate to the junction box.

9. An electrical switch comprising a cup, contact devices secured to the interior of the cup, switch blades that are progressively ro- 125 tatable parallel to the side walls of the cup into and out of engagement with the contact devices, and mechanism for operating

said blades with a snap action including a pull cord.

10. An electrical switch comprising a cup, contact devices secured to the interior of the cup, a bracket secured to the open end of the cup, a progressively rotatable switch member carried by said bracket provided with means adapted to coöperate with the contact

devices, and operating mechanism for said switch member including a pull cord.

10
In testimony whereof I affix my signature in presence of two witnesses.

ALLEN A. TIRRILL.
